UNITED STATES PATENT OFFICE.

HENRY GEORGE FEDI, OF DULUTH, MINNESOTA, ASSIGNOR OF ONE-THIRD TO WENCHEL
W. SOUKUP, OF DULUTH, MINNESOTA.

LIFE-BOAT.

1,152,158.

Specification of Letters Patent. Patented Aug. 31, 1915.

Application filed October 31, 1914. Serial No. 869,554.

To all whom it may concern:

Be it known that I, HENRY GEORGE FEDI, a citizen of the United States, residing at Duluth, in the county of St. Louis and State 5 of Minnesota, have invented certain new and useful Improvements in Life-Boats, of which the following is a specification, reference being had therein to the accompanying drawing.

- 10 This invention relates to improvements in life boats, and has for its object to produce a boat of large carrying capacity and one requiring comparatively little space aboard ship.
- 15 Another object is to provide such a boat having all the necessary conveniences and accommodations readily available so that a comparatively long while may be spent within the boat upon an open sea with but little 20 inconvenience.

Other objects will become apparent as the construction of the device is understood from the specifications and claims.

In the accompanying drawings forming a 25 part of this application: Figure 1 is a top plan view of my improved boat, illustrating it adjusted and ready for service as a life boat. Fig. 2 is a vertical longitudinal section through the center of the boat. Fig. 3 is a transverse vertical section just abaft 30 the forward thwartship beam, illustrating one of the side portions as being stowed as when aboard ship, and the other side portion as being shipped for navigation. Fig. 35 4 is a plan view of one of the adjustable oarlocks. Fig. 5 is a plan view of one of the collapsible oarsmen's seats, in its collapsed position. Fig. 6 is a side elevation of Fig. 5, except that the seat is illustrated in its upper 40 right position. Fig. 7 is a vertical section through one side of the cockpit and running board, illustrating the relative position thereof and that of the adjustable step upon the running board.

45 The general construction of my improved boat is more in the form of a catamaran in that the accommodations for passengers is mounted upon the upper deck of the pontoons comprising the boat or raft rather than within the hulls thereof.

50 Referring now to the drawings in which like reference numerals designate similar parts, 1 represents the major central hull or pontoon, having spaced upon either side thereon the minor pontoons 3—3, each of

the latter being pivotally supported therefrom by means of suitable hinges 4 upon the ends of the two athwart beams 5 and 6, 5 being adjacent the bow end of the pontoon 1, and 6 being adjacent the stern end thereof, and the amidship beam 7. These three beams are rigidly fixed to the upper deck of the pontoon 1 and are suitably braced diagonally by braces 8 to properly strengthen the same against abnormal usage.

60 The pontoons 1, 2 and 3 are made of any desirable material, either wood or metal, and are formed with the greatest carrying capacity consistent with easy and well formed lines, they being made air and 65 water-tight except as to certain compartments within the pontoon 1, which will be more fully described later.

70 A strong upright standard 9 is placed integral with the forward edge of the beam 5 and in the center line of the hull 1, and a similar standard 10 is placed integral with the after edge of the beam 6, these standards being securely fastened to their respective beams and to the deck of pontoon 1.

75 Upon the upper edge of the standard 9 is pivotally mounted by means of the hinge 12 the mast 13 for carrying any form of suitable sail 14 and jib 15 and such signaling means desired, as a light 16, or flag or both.

80 Angle brackets 17—17 are formed upon either side of the foot of the mast 13 and are integral with the standard 9 and deck of the pontoon, they being for the purpose of stiffening the standard and acting as a guide 85 and stay to the foot of the mast, the latter being raised and lowered by means of a suitable line 18 passing through the base of the standard and attached to the foot of the mast.

90 Angle brackets 17—17 are formed upon either side of the foot of the mast 13 and are integral with the standard 9 and deck of the pontoon, they being for the purpose of stiffening the standard and acting as a guide 95 and stay to the foot of the mast, the latter being raised and lowered by means of a suitable line 18 passing through the base of the standard and attached to the foot of the mast.

95 A bail 19, preferably, passes around the entire hull of the pontoon 1 and extends to a point central with the upper end of the standard 9 where it is formed into a suitable eye 20 for the reception of the davit hooks or the like for the raising and lowering of the entire boat, as when being shipped or unshipped in relation to the vessel carrying same. This bail is also rigidly fixed to the standard 9 to further strengthen and stiffen 100 the entire structure.

105 The standard 10 carries bail 21, having an eye 22 similar to that at the forward end of the boat, this bail also being primarily for the purpose of suspending the boat.

Attached to each side of both standards 9 and 10 is a chain 23, the opposite end of each of which leads to a strong strap eye 24, fixed to the extreme outer edge of the minor pontoon, there being two of such upon the outmost edge of each pontoon, and as is clearly evident these chains are for additional supporting means to counteract the overhanging of the minor pontoons as well as forming ready means for raising the pontoon upon its pivotal centers to its stowed position as illustrated upon the left side of Fig. 3.

Within the standard 10 is revolvably mounted a shaft 25 carrying upon its innermost end a suitable steering wheel 26 readily accessible from the passengers' quarters and having upon its outermost end, a spool or drum 27 about which the steering line 28 is wound and the opposite ends of which lead to opposite sides of the tiller 29 controlling the rudder 30 of the boat, providing simple convenient means whereby the boat is steered.

Upon each side of the standards 9 and 10 is pivotally supported, by means of suitable heavy hinges 31, an angular shaped swinging bracket or strut 32, they being designed to swing out over the minor pontoons when the latter are shipped below their supporting beams preparatory to navigation, and firmly hold them in place. The free end of each of said struts is designed to engage a normally upwardly extending spring catch 33 for holding the strut securely in place, and which necessitates unlocking before the strut can be swung about over the major hull as indicated in dotted lines Fig. 1 when the boat is stowed. These struts may be of any desired construction to answer the purpose, but are here shown as being constructed of wood and properly braced to form a substantial structure.

Intermediate the minor hulls or pontoons and the major pontoon and supported upon the athwartship beams, are rigidly fixed running-boards 34—34, one upon each side, and upon these running-boards are arranged collapsible seats 35 for the accommodation of those who man the boat and manipulate the oars for the propulsion of the vessel when occasion necessitates. I have illustrated these seats as composed of an upright back portion 36 hinged at 37 to the running-board, and having hinged upon its upper edge the seat proper 38 which, when erected as shown in Fig. 6, rests at right angles to the back upon the two hinged wings 39 and 40 which latter are hinged to the side of the back when collapsed, fold inwardly upon the back as shown in Fig. 5.

Upon one of the running-boards 34 I have provided a pivotally hinged step 41, designed to rest normally lying flat upon the running-board, see Fig. 7. When raised for

use, this step reclines against the side wall of the passengers' quarters and provides easy access thereto, but may be quickly dropped to a reclining position to be out of the way of the minor pontoon when stowed, 70 the seats above referred to, being collapsible for the same purpose.

Intermediate the running-boards and the major hull and upon the athwartship beams, 5, 6, and 7, may be fixed suitable staples 42 75 for the reception of the oars not in use, or any other convenient arrangement may be made for their compact storage.

I have provided collapsible oar-locks upon the upper deck of the minor pontoon as illustrated in Figs. 1 and 4, each of which comprises the pivotally hinged member 43 which is attached to deck of the pontoon in such a manner as to be placed down flat upon the deck as shown in Fig. 4, when the boat is 85 stowed away or raised upright as shown in Fig. 1, for the purpose of supporting the oars, each member 43 having a suitable recess 44 therein, for the reception of the oars. A support 45 is also hinged to the deck intermediate the hinged ends of the oar-lock 43 and having a notch 46 in the free end thereof so when raised to an upright position under the member 43, it will straddle the same and form a suitable support against 95 any lateral movement of the oar-lock.

A block 47 is fixed to the deck of the pontoon adjacent the support 45 and upon which is pivoted a button 48 which is designed to be adjusted to overlap both the support 45 100 and the oar-lock member 43 when they are collapsed at the time of stowing the boat.

Upon the major pontoon or hull 1 and intermediate the beams 5 and 6 and the running boards 34—34 is provided accommodations for passengers and comprises an upright continuous wall 49 extending around the entire space above referred to, and which wall is provided with a plurality of suitable swinging limber doors 50, there being preferably two on each side. These doors are made to swing outwardly only, so that in the event of water entering the pit formed by the wall 49, it may readily pass out through the limbers and the pit thus becomes 110 self-bailing.

If preferred the limber doors 50, may be provided with a suitable line attachment 61 which may lead to an accessible place within the pit to admit of the doors being actuated manually if preferred.

Upon the upper edge of the wall 49 along the sides of the pit is integrally fixed the seats 52—52, they being wide and commodious for the accommodation of the passengers and preferably projecting outwardly considerably beyond the wall 49, and from which outer edge, extends both above and below the vertical wall 53 which forms a strong suitable back to the seats and wall to the pit. 130

At the forward end of the pit the seat 54 is somewhat narrower for convenience in operating the mast, sails, etc. At the after end of the pit the seat 55 which is a continuation of the seat 52 does not extend the entire distance across the pit, but is terminated by an upright division board 56 which extends somewhat higher than that of the head of a person sitting upon the seat 55 and upon the opposite side of which is installed within the extreme after end of the seat 52 upon that side of the boat a suitable water closet seat 57 for the convenience of the passengers, and division board 56 forming a shield for same.

The floor of the pit is covered with suitable elevated slats 58, as is common in nautical practice.

Within the central portion of the major pontoon 1, is a rectangular shaped watertight compartment 67, in which is slidably installed a box 68 having its entire upper wall open and at all times communicating with the hatchway 59 through the upper deck of the pontoon. This hatchway 59 is surrounded by a suitable coaming 60 having a hinged hatch cover 61 thereover. A rope 62 is fastened to the forward end of the box 68 and within the interior thereof and leads up through the hatchway 59 and out through the forward wall of the coaming thereof. A similar rope 63 is fastened to the opposite end of the box and leads through the opposite side of the coaming to that of the previously mentioned rope, and it is evident that by means of these ropes, the box 68 may be slid back and forth within the compartment 67, and thereby provide means of access to the entire box for the placing within or removing goods from the box, thus providing a simple and commodious commissary compartment for the accommodation of the passengers within the boat.

In the forward end of the major pontoon is formed a wall or compartment 64 of any size desired for the storage of blankets and the like and which is covered with a hatch cover 65. In the after portion of the major pontoon, I have illustrated a tank 66 which is designed for the storage of fresh water and may be of any desired size and accessible in any desired manner, either by means of a pump or dipper arrangement.

From the foregoing it will be seen that I have provided a simple, compact, and practical life boat or raft which may be carried by most any form of vessel, and one which occupies comparatively little space when

stowed away on ship-board, yet quickly and easily adjusted and manned for any contingency at sea.

Having thus fully described my invention what I claim and desire to secure by Letters Patent is:

1. A life boat of the character described comprising a major pontoon, a plurality of fixed beams athwart the said pontoons, two minor pontoons hinged to the outer ends of the said beams one on each side of the major pontoon, flexible means connecting the minor pontoons and the major pontoon for raising and lowering the former, rigid braces hinged to the major pontoon and swung outwardly over the minor pontoons for holding the minor pontoons rigid when in their lowered position, and a deck and passengers' quarters carried by the major pontoon and the rigid beams carried thereby.

2. A life boat of the character described, comprising a major pontoon, a plurality of fixed beams athwart the said pontoon, two minor pontoons hinged to the outer ends of the said beams, one on each side of the major pontoon, running boards arranged between the minor pontoons and the major pontoons, oarsman's seats located on said running boards, said seats collapsible, oar-locks on the minor pontoons in a line with the oarsman's seats, said oar-locks collapsible, the parts arranged as and for the purpose described.

3. A life boat of the character described comprising a major pontoon, a plurality of fixed beams athwart the said pontoon, two minor pontoons hinged to the outer ends of the said beams one on each side of the major pontoon, and running boards arranged between the minor pontoons and the major pontoon, oarsman's seats located on the said running boards, the parts arranged as and for the purpose described.

4. A life boat of the character described comprising a major pontoon, a plurality of fixed beams athwart the said pontoon, two minor pontoons hinged to the outer ends of the said beams one on each side of the major pontoon, a deck carried by the major pontoon and the upper surface of the beams, and oarlocks mounted upon the minor pontoons providing means whereby the boat may be propelled.

In testimony whereof I hereunto affix my signature in the presence of two witnesses.

HENRY GEORGE FEDI.
